ATTORNEY.

UNITED STATES PATENT OFFICE.

CHARLES BERNARD, OF GARY, INDIANA.

WRENCH.

1,367,730.

Specification of Letters Patent.

Patented Feb. 8, 1921.

Application filed September 14, 1920. Serial No. 410,165.

To all whom it may concern:

Be it known that I, CHARLES BERNARD, a citizen of the United States, residing at Gary, in the county of Lake and State of Indiana, have invented certain new and useful Improvements in Wrenches, of which the following is a specification.

This invention relates to a wrench and contemplates an improvement whereby the jaws thereof may be quickly adjusted in respect to each other and to generally improve upon the structure thereof by providing a wrench which will be extremely simple, durable and inexpensive in construction, one which is efficient and reliable in operation and well adapted to the purpose for which it is designed.

Numerous other objects will become apparent from the annexed specification and it will be seen that the invention resides in certain novel features of construction, and the combination and arrangement of parts as will be hereinafter fully described and claimed.

25 In the drawing:—

Figure 1 is a side elevation of the wrench, and

Figs. 2 and 3 are sections taken on the lines 2—2 and 3—3 of Fig. 1 respectively.

30 Referring to the drawing in detail it will be seen that 1 designates the handle of the wrench which is provided at one end with a head 2. A fixed jaw is mounted upon the upper end of the head 2 as indicated at 3 and disposed at one side thereof. A projection 4 is provided upon the head 2 and is formed with the rib 5 having ledges upon both sides thereof which are serrated so as to form the teeth 6. This rib 5 may be 35 either formed integral with the head 2 or separated therefrom so as to be replaceable.

The movable jaw 7 is provided with a slot 8 as is shown in Fig. 2 which will ride over the rib 5 thus preventing the lateral movement of the jaw 7 in respect to the head 2. This movable jaw 7 is therefore slidably mounted upon the rib 5 and the lower portion of the jaw 7 upon each side of the groove 8 is serrated so as to form a piece 50 which will mesh with the teeth 6 and prevent the sliding movement of the movable jaw 7. As thus far described it will be seen that the movable jaw 7 may be lifted and moved closer or farther from the fixed jaw 3 as may be desired. In order to hold the

movable jaw 7 down in fixed engagement with the head 2 by having the teeth of the movable jaw in mesh with the teeth 6 on the head 2 I have provided a guide 9 which is U-shaped and has its ends pivotally mounted upon the head 2 by means of a rivet 10. The side portions of the movable jaw 7 are provided with the grooves 11 into which the legs of the guide 9 extend so that the jaw 7 may be slid therebetween. A leaf 65 spring 13 having an outwardly bent portion 14 is situated upon the end of the nose 4 and is held in place by means of a screw 15. Thus it will be seen that the outward projecting portion 14 will engage the upper side 70 of the connecting piece of the guide 9 for holding the movable jaw 7 down into engagement with the head 2.

When it is desired to use the wrench the movable jaw 7 will preferably be spaced as 75 far from the fixed jaw 3 as possible and the nut upon which it is desired to use the wrench will be situated therebetween. By pressing inwardly upon the outwardly projecting portion 14 the movable jaw 7 may be 80 pushed toward the nut and into form engagement therewith since the guide 9 will now allow same to rise slightly so as to pass over the teeth 6 on the head 2. These teeth 6, of course, will be so slanted as to allow 85 the movable jaw 7 to be pushed inwardly but prevent same from being pushed outwardly without first lifting the jaw.

From the foregoing description, taken in connection with the accompanying drawing, 90 the construction and operation of the wrench will be readily understood without a more extended explanation. As numerous changes in form, proportion, and in the minor details of construction may be resort- 95 ed to without departing from the spirit of this invention, I do not wish to be limited to the construction herein shown and described other than as claimed.

Having thus described my invention what 100 I claim as new is:—

1. A wrench comprising a head, a fixed jaw mounted thereon, a movable jaw slidably mounted on the head, means for preventing lateral movement of the movable jaw, a guide pivotally mounted upon the head and having the movable jaw slidably therein, and means for engaging the guide so as to hold the movable jaw fixed on the head. 110

2. A wrench comprising a head, a fixed jaw mounted thereon, a movable jaw slidably mounted on the head, means for preventing lateral movement of the movable jaw, a guide pivotally mounted upon the head, the movable jaw provided with grooves for receiving the guide so as to be slidable therein, and means for engaging the guide so as to hold the movable jaw fixed on the 10 head.

3. A wrench comprising a head, a fixed jaw thereon, a movable jaw slidably mounted on the head, means for preventing lateral movement of the movable jaw, a guide being 15 substantially U-shaped and having its ends pivotally mounted upon the head, the movable jaw provided with grooves for receiving the legs of the guide so as to be slidable therebetween, and means for engaging the 20 guide so as to hold the movable jaw fixed on the head.

4. A wrench comprising a head, a fixed jaw thereon, a movable jaw slidably mounted on the head, means for preventing lateral 25 movement of the movable jaw, a guide pivotally mounted upon the head, the movable jaw provided with grooves for receiving the guide so as to be slidable therein, and a spring fixedly attached to the head and having 30 an outward projecting portion for en-

gaging the guide so as to hold the movable jaw fixed on the head.

5. A wrench comprising a head, a fixed jaw thereon, a rib mounted on the head, a movable jaw having a slot therein, for receiving the rib so as to be slidably mounted upon the head, a guide pivotally mounted on the head, the movable jaw provided with grooves for receiving the guide so as to be slidable therein, and means for engaging the 40 guide so as to hold the movable jaw fixed on the head.

6. A wrench comprising a head, a fixed jaw thereon, a rib mounted on the head, a movable jaw having a slot therein for receiving the rib so as to be slidably mounted upon 45 the head, a guide having a substantially U-shape and having its ends pivotally mounted upon the head, the movable jaw provided with grooves for receiving the legs 50 of the guide so as to be slidable therebetween, and means for engaging the guide so as to hold the jaw fixed on the head.

In testimony whereof I affix my signature in presence of two witnesses.
